UNITED STATES PATENT OFFICE.

CHARLES L. ALLEN, OF PEWAUKEE, WISCONSIN.

STOVE-LEG.

SPECIFICATION forming part of Letters Patent No. 550,239, dated November 26, 1895.

Application filed May 23, 1895. Serial No. 550,343. (No model.)

To all whom it may concern:

Be it known that I, CHARLES L. ALLEN, a citizen of the United States, and a resident of Pewaukee, in the county of Waukesha and 5 State of Wisconsin, have invented certain new and useful Improvements in Stove-Legs; and I do hereby declare that the following is a full, clear, and exact description thereof.

My invention has for its object to facilitate 10 handling of stoves; and it consists in certain peculiarities of construction and combination of parts hereinafter set forth with reference to the accompanying drawings, and subsequently claimed.

15 In the drawings, Figure 1 represents a section taken on line 1 1 of Fig. 2, and illustrates my improvements in connection with a stove-base; Fig. 2, a similar view on line 2 2 of Fig. 1, and Fig. 3 a like view on line 3 3 of Fig. 1.

20 Referring by letter to the drawings, A represents a stove-base provided with the usual ledges *b*, arranged in pairs for engagement of horizontal flanges *c*, that extend inward from the upper ends of the stove-legs, and I prefer 25 to provide each leg-flange with a set-screw *B*, that is run up against said stove-base. By means of the set-screws in the flanges *c*, I take up loose play and thus bind said flanges tight on the ledges *b*, thereby preventing accidental 30 disengagement of the legs from the base.

The upper portion of the leg is made in the form of a socket *d* for a vertical shank *e*, having an annular groove *f*, engaged by the inner end of a screw *g*, run through the wall of the

35 socket. By means of the screw the shank is held against vertical displacement when the stove is lifted.

The shank *e* is part of a fork *h* in which the caster-wheel *i* is journaled, and I show 40 the entire caster held rigid by means of a plug in the form of a screw *j*, extending through a base-curtain or leg-shield *C* into a tapped re-

cess in said wheel, the curtain or shield being also shown connected with the upper socket portion of the stove-leg by a screw *k*, that engages a tapped opening in said leg, but it may be joined to the stove-base, and it is also practical to lock the caster-wheel by means other than those herein set forth, especially if no curtain or shield be employed.

It will be noticed that the base-curtain or leg-shield extends down close to the surface on which the wheels rest, and not only hides the legs but imparts finish to the stove.

From the foregoing it will be understood 55 that when the curtain or shield is removed the caster-legs are free, and a heavy stove having such legs may be readily moved from one place to another with but little effort; but when said curtain or shield is in place, as herein shown, said caster-legs cannot swivel, and the caster-wheels being held against possible rotation the stove is not liable to slip out of position.

Having thus described my invention, what 65 I claim as new, and desire to secure by Letters Patent, is—

1. A stove-leg in the form of a caster, a fixed shield for the leg, and a screw that extends through the shield into a recess in the 70 caster-wheel.

2. A stove-leg in the form of a caster, a shield in detachable connection with the socket portion of the caster, and a suitable plug detachably engaging the shield and the 75 caster-wheel.

In testimony that I claim the foregoing I have hereunto set my hand, at Milwaukee, in the county of Milwaukee and State of Wisconsin, in the presence of two witnesses.

CHARLES L. ALLEN.
